UNITED STATES PATENT OFFICE.

JOHN K. PUNDERFORD, OF NEW HAVEN, CONNECTICUT.

VEHICLE-LAMP.

No. 925,720.

Specification of Letters Patent. Patented June 22, 1909.

Application filed January 18, 1909. Serial No. 472,896.

To all whom it may concern:

Be it known that I, JOHN K. PUNDERFORD, a citizen of the United States, residing at New Haven, in the county of New Haven 5 and State of Connecticut, have invented a new and useful Improvement in Vehicle-Lamps; and I do hereby declare the following, when taken in connection with the accompanying drawings, and the numerals of 10 reference marked thereon, to be a full, clear, and exact description of the same, and which said drawings constitute part of this specification, and represent, in—

Figure 1 a front view of a lamp constructed 15 in accordance with my invention showing a screen interposed between the burner and the reflector. Fig. 2 a sectional view of the same and also illustrating means for reducing the light. Fig. 3 a sectional view of the 20 screen shown in the preceding figures in the closed position. Fig. 4 a sectional view showing the inside of one of the walls of the tube. Fig. 5 a side view of one of the intermediate fan leaves, detached. Fig. 6 a 25 sectional view at right angles to that shown in Fig. 3.

This invention relates to an improvement 30 in vehicle lamps, and particularly to those of the search-light character used in automobiles, motor boats, etc.

It is a well known fact that when two vehicles are approaching each other, the headlight and search-light of one vehicle so blinds the eyes of the driver of the other vehicle that it is impossible for either to see any obstructions which may be in their path.

The object of this invention is to temporarily suppress the action of the reflector by interposing a device between the burner and 40 the reflector, and the invention consists in the construction as hereinafter described and particularly recited in the claims.

The objects of this invention may be accomplished in a variety of ways. Thus means 45 may be arranged between the burner and the reflector to temporarily suppress the action of the reflector. As clearly shown in Figs. 1 and 2 of the drawings, this device may be in the form of a fan comprising swinging 50 leaves 2, more or less in number, arranged in front and rear of a vertically movable leaf 3 which is connected to the upper end of a vertically guided rod 4 moving in a vertically 55 arranged tube 5 and mounted in the lamp body 6 in rear of the burner 7 and in front of

the reflector 8. It will be noted that the tube is arranged in line with the burner, and preferably and as shown, corresponds substantially in diameter to the diameter of the tube, or at least is no wider than the tube so 60 that no additional shadow is cast by it. In order to spread the fan the front and rear walls of the upper end of the tube are formed with cam surfaces 9, and the outer leaves formed with studs 10 to coact therewith. This outer leaf carries a pin 11 which enters a slot 12 formed in the next leaf, and so on, so that when the rod 4 is raised, the leaves will be pushed out of the upper end of the tube, and as they emerge therefrom will 70 be spread as indicated in Fig. 1.

It will be clearly understood, without further illustration, that the rod 4 may be raised and lowered from any convenient point in the vehicle either by a foot or hand 75 lever, by a pneumatic bulb, or other well known means for operating similar parts.

With a device of this character, when two vehicles are approaching each other, if the rod 4 be raised to open the fan between the 80 light and the reflector, the action of the reflector is suppressed. The burner, however, is not affected, and the light therefrom will be sufficient to enable one driver to see the course of the other. As soon as the vehicles 85 pass it is only necessary to reverse the movement to draw the fan into the tube.

It will be understood that by the term "burner" as used herein, I wish to be understood as including a gas burner, oil burner, 90 or electric light.

I claim:

1. In a lamp, the combination with a burner and reflector, of a tube located between the burner and reflector and in line 95 with said burner, a vertically movable rod in said tube, and fan-like leaves connected with said rod and adapted to be projected and spread above said top of said tube.

2. In a lamp, the combination with a 100 burner and reflector, of a tube located between the burner and reflector in line with and corresponding in diameter to the diameter of the burner, a vertically movable rod in said tube, and fan-leaves connected with 105 said rod and adapted to be projected and spread above the top of said tube.

3. In a lamp, the combination with a 110 burner and reflector, of a tube located between the burner and reflector, a vertically

movable rod in said tube, and fan-leaves connected with said rod and adapted to be projected and spread above the top of said tube.

4. In a lamp, the combination with a burner and reflector, of a tube located between the burner and reflector, a rod in said tube, a central leaf connected with said rod, a series of leaves connected with said central leaf, cam-surfaces in said tube, pins in the outer leaves adapted to engage with said cam surfaces, and pin and slot connections between the leaves whereby when the central leaf is raised, the other leaves will be spread above the tube.
- 10 5. In a lamp, the combination with a burner and reflector, of a tube located be-

tween the burner and reflector, a vertically movable rod in said tube, and a screen carried by said rod and adapted to be spread above the top of said tube.

- 20 6. In a lamp, the combination with a burner and reflector, of a folding screen located in rear of said burner and adapted to be spread between the top of the burner and reflector.

25 In testimony whereof, I have signed this specification in the presence of two subscribing witnesses.

JOHN K. PUNDERFORD.
